UNITED STATES PATENT OFFICE.

GUSTAV ZOHNER, OF FORRES, SASKATCHEWAN, CANADA.

ANIMAL-RELEASING DEVICE.

1,242,302.

Specification of Letters Patent.

Patented Oct. 9, 1917.

Application filed May 24, 1916. Serial No. 99,693.

To all whom it may concern:

Be it known that I, GUSTAV ZOHNER, a citizen of Canada, residing at Forres, in the Province of Saskatchewan, in the Dominion of Canada, have invented certain new and useful Improvements in Animal-Releasing Devices, of which the following is a specification.

This invention relates to improvements in animal releasing devices and its object is to provide means whereby a number of animals confined in stalls in a barn may be simultaneously released by mechanism operable from outside the barn. A further object is to provide an easily operated device that may be cheaply installed in a barn that will operate with maximum efficiency. With the foregoing and other objects in view the invention consists in the combination and arrangement of parts to be hereinafter fully described in this specification, pointed out in the appended claims and illustrated in the accompanying drawings which form a part of said specification and in which—

25 Figure 1 is a fragmentary view of a barn showing the application of my improved device.

Fig. 2 is an enlarged fragmentary view of Fig. 1 showing the hitching ring released.

30 Fig. 3 is an end view of Fig. 2 but with the device in assembled or operative position.

Fig. 4 is a section taken on line 4—4 of Fig. 3.

35 Fig. 5 is a fragmentary view of Fig. 4 with the ring in released position.

Fig. 6 is a detail of the locking pin and the bar carrying the same.

Like reference characters denote corresponding parts throughout the several views.

The reference numeral 1 denotes the barn which is divided into stalls 2 and to the manger wall 3 in each stall angular guide brackets 4 are secured, one end of said

45 brackets abutting the top rail 5 of the manger wall. A pull rod 6 extends through one end of the barn and along the manger wall and through the several brackets 4 and is slotted longitudinally as at 7 in each stall

50 to receive the hooked link 8 which pivotally carries the locking pin 9 and through the hooked end of which a pivot 11 extends that is carried by the said rod 6. Through a perforation 12 in the manger wall the smaller

55 end of a Y-shaped bracket 13 extends, said end being adapted to receive the said pin

9 whereby the bracket is releasably locked in position. The bracket 13 is formed of a resilient material and its open ends terminate in eyes 14 that serve as bearings for the 60 diametrically opposed lugs 15 of the hitching ring 16 to which the snap 17 of the hitching strap 18 is secured. It will be noted that the link 8 normally rests, at an oblique angle with the pull rod, against the 65 bracket 4 while the pin 9 is in engagement with the bracket 13.

To the end of the pull rod 6 outside the barn an operating lever 19 is secured, said lever being pivoted to a stud 20 carried by 70 the barn. In Fig. 1 the device is shown in operative position. To release the rings 16 simultaneously the lever 19 is moved upon its pivot away from the barn thus moving the rod 6 and, with it, the several links 8 75 which as they are drawn through the brackets 4 are raised into the slotted portions 7 of the pull rod thus withdrawing the pins 9 from brackets 13 that carry said rings 16 and so freeing the latter which the several 80 animals in the stalls may take with them upon their straps 18 as they leave the barn or stable. The device is reassembled by moving the pull rod back to initial position, re-inserting the brackets 13 into the manger 85 wall and placing the pins 9 and rings 16 in engagement with said brackets.

What is claimed is:—

1. The combination with a slotted pull rod and an operating lever therefor, of links 90 pivotally hung in the slotted portions of said pull rod, angular guide brackets for said pull rod normally in supporting engagement with said links to retain them at an oblique angle with said pull rod, resilient 95 Y-shaped brackets arranged below the slotted portions of said pull rod, hitching rings releasably carried by said brackets and pins pivotally carried by said links for releasable engagement with the smaller or closed 100 ends of said Y-shaped brackets.

2. The combination with a supporting element formed with suitable perforations, of a slotted pull rod, links pivotally hung in the slotted portions of said pull rod, angular 105 guide brackets for said pull rod normally in supporting engagement with said links to retain them at an oblique angle with said pull rod, resilient Y-shaped brackets arranged below the slotted portions of said pull rod and having their smaller or closed 110 ends passed through the perforations of said

supporting element, hitching rings releasably retained in the open ends of said Y-shaped brackets, pins pivotally carried by the aforesaid links for releasable engagement with the smaller ends of said Y-shaped brackets, and an operating lever for said pull rod.

3. The combination with a supporting element formed with suitable perforations, of a slotted pull rod, an operating lever for said pull rod, links pivotally hung in the slotted portions of said pull rod, pins pivotally carried by said links, resilient Y-shaped brackets having their closed ends passed through the perforations in said supporting element to receive the aforesaid pins, hitching rings releasably carried by the open

ends of said Y-shaped brackets and means carried by said supporting element for supporting and guiding said pull rod and for retaining said links at an oblique angle with said pull rod while the latter member is in its normal position and for moving said links wholly into the slotted portions of said rod as the latter member is moved in one direction by the said operating lever.

In testimony that I claim the foregoing as my own I have hereto affixed my signature in the presence of two subscribing witnesses:

GUSTAV ZOHNER.
